UNITED STATES PATENT OFFICE.

CHARLES S. SMITH, OF MILWAUKEE, WISCONSIN, ASSIGNOR TO A. O. SMITH CORPORATION, OF MILWAUKEE, WISCONSIN, A CORPORATION OF NEW YORK.

PROCESS OF AND APPARATUS FOR MAKING CORRUGATED-METAL RAILWAY-CAR ENDS WITH INTEGRAL ATTACHING FLANGES.

Application filed October 30, 1924. Serial No. 746,717.

My invention resides in an improved method of transforming or converting flat metal blanks into sheets having a corrugated central section and plain side marginal portions forming integral flanges by means of which the sheet may be attached to the end of the railway car, and it consists in subjecting such a flat blank to the action of corrugating rollers to produce the desired configuration of the central portion, and the same time turn the side marginal portions so that the latter will stand in planes normal to that of the sheet to form the attaching flanges.

The invention also resides in an improved machine provided with longitudinally grooved rollers which are adapted to form the corrugations in the plates, such rollers also being constructed so as to turn the side flanges in the corrugating operation.

My improvement has greatly simplified the manufacture of structures of this class, by eliminating some of the separate operations heretofore performed, and permits the production of a completed corrugated car end with its attaching flanges by a single operation.

The invention will now be more fully disclosed, and the novelty residing therein will be pointed out in the appended claims.

In the accompanying drawing:

Figure 1 is a vertical longitudinal sectional view of a simple form of an apparatus embodying one aspect of the invention, and by means of which my improved process may be carried out.

Fig. 2 is a vertical sectional view taken in the axial line of the rollers and showing the formation of the flange producing construction.

Referring now to the drawing, the numerals 10 and 11 indicate upper and lower fluted driven rollers journaled at their ends in stands 12, one of which is shown. The upper roller 10 is flat at its ends and is grooved or ribbed throughout its length. The lower roller 11 is similarly grooved or ribbed for a portion of its length corresponding to the same formation in the roller 10, with which it co-operates, and is provided at its ends with circumferential flanges 13.

A work table 14 is associated with the rollers, the top of the table being in the plane

of the meeting line of the rollers. The metal sheet 15 from which the corrugated and flanged integral car end is formed is passed over the top of the table and under a pressure roller 16 journaled at its ends in the stands 12, the roller 16 serving to hold the sheet flat upon the table and acting also as a feeding roller to effect the movement of the metal sheet.

By reason of the ductile nature of the metal sheet 15, the surface of the sheet is easily distorted from its mill state as it passes between the rollers 10 and 11, and is converted into the desired formation. In such operation, the flanges 13 at the ends of the roller 11 turn up the plain side margins of the metal sheet, and press such margins against the ends of the roller 10, to form the attaching flanges 17 for the car end, so that such margins or flanges will then stand in planes which are normal to that of the sheet. At the same time, the rollers 10 and 11 form the transverse corrugations 18 in that portion of the sheet which extends between the upturned flanges.

A guiding plate 19, supported by depending arms 20, is spaced from the top of the table and parallel therewith at the rear of the rollers so as to permit the passage of the corrugated section 18 of the sheet, and at the same time confine the sheet so that it will emerge in a flat plane. Vertically disposed longitudinal guides 21 are arranged at the sides of the table at the rear of the rollers 10 and 11, so as to direct the flanges 17 of the corrugated sheet in their upstanding positions.

By means of the very simple apparatus shown, I am enabled to transform flat metal sheets into corrugated sheets with the side margins upturned so as to constitute the attaching flanges, and in doing so I have eliminated many of the operations incident to the production of structures of this class by known methods, and have also greatly reduced the cost of their production. The molecules of the metal sheet flow freely under the combined pressures exerted, so that the sheet readily assumes the formation desired in passing through the rollers.

Having thus described my invention what I claim and desire to secure by Letters Patent of the United States, is:

1. The method of producing railway car

ends formed as corrugated plates with integral flanges, which consists in providing a pair of rollers having corrugations less in length than the width of the metal sheet, 5 passing the sheet through the rollers so as to corrugate the central section thereof, and in the same operation turning the side margins of the sheet into flanges standing normal to the plane of the sheet, and guiding 10 the corrugated and flanged plate so as to preserve the plane thereof.

2. In a machine for converting flat metal sheets into corrugated plates with integral flanges for attachment to the ends of a rail- 15 way car, fluted rollers through which the sheets are passed to produce the corrugations, and co-operating means at the ends of the rollers for turning the flanges into positions normal to the plane of the sheet, and 20 means for guiding the corrugated sheet through the machine to preserve it in the plane of its corrugations.

3. In a machine for converting flat metal sheets into corrugated plates with integral flanges for attachment to the ends of a 25 railway car, a fluted roller flat at its ends and a co-operating fluted roller provided with flanges at its ends to turn the margins of the sheets against the flat ends of the first roller and into planes normal to that of the sheet. 30

4. In a machine for converting flat metal sheets into corrugated plates with integral flanges for attachment to the ends of a rail-

way car, a fluted roller flat at its ends and a 35 co-operating fluted roller provided with flanges at its ends to turn the margins of the sheets against the flat ends of the first roller and into planes normal to that of the sheet, 40 and means for guiding the corrugated and flanged plate through the machine.

5. In a machine for converting metal sheets into corrugated plates with integral flanges at the sides for attachment to the ends of railway cars, a pair of fluted rollers 45 acting to produce such corrugations and provided with means at their ends for turning the margins of the sheet to form the said flanges, and means for guiding the corrugated and flanged sheet through the ma- 50 chine.

6. In a machine for converting metal sheets into corrugated plates with integral flanges for attachment to the ends of a rail-way car, a pair of fluted rollers between 55 which the sheet is passed and by which its central portion is corrugated, one of such roll- 60 ers having flat ends and the other having flanges to turn the margins of the sheet into planes which are normal to the plane of the sheet, a table over which the sheet is passed, and means at the rear of the rollers for guiding the corrugated and flanged plate to 65 preserve it in the plane of the corrugations.

In testimony whereof, I have signed my name at Milwaukee, this 27th day of October, 1924.

C. S. SMITH.
